UNITED STATES PATENT OFFICE.

OTTO W. JOHNSON, OF OAKLAND, CALIFORNIA.

FURRING STAPLE.

Application filed June 16, 1924. Serial No. 720,365.

My invention relates to furring devices, and more particularly to a furring staple for spacing the wire-mesh reinforcement of a plastered wall a fixed distance from the 5 wall surface.

I am aware of small furring devices on the market for the above purpose, but I have found that they are deficient to the extent that the tops or heads of the said 10 devices project above the top surface of the laid or positioned wire-mesh lathing. These projections are quite objectionable in applying the plaster to the wall, as they interfere in the spreading of the plaster flush with 15 the lathing surface. In such application, the plasterer's float or darby continually strikes the said heads and much to the annoyance of the plasterer. The ultimate result is, that the progress of the work is slowed 20 up to a certain extent, considerable plaster is dropped and lost by the shock of impact with the heads, and the surface of the darby is subjected to quick wear.

The objects of my present invention are 25 to overcome the just recited objections, and I attain the desired results by the novel construction of my simple, efficient and inexpensive staple.

The invention possesses other advantageous 30 features, some of which, with the foregoing, will be set forth at length in the following description where I shall outline in full that form of the invention which I have selected for illustration in the drawings accompanying 35 and forming part of the present specification. In said drawings I have shown one form of my invention, but it is to be understood that I do not limit myself to such form, since the invention, as expressed in the 40 claims, may be embodied in a plurality of forms.

Referring to said drawings:

Figure 1 is a perspective view of the staple 45 constructed in accordance with my invention, and is as normally sold and received by the user. Figs. 2 and 3 show the two parts of the staple segregated.

Fig. 4 is a plan of the staple in use before 50 the furred wall has received the first coat of plaster. Fig. 5 is a sectional side elevation of the portion of wall shown in the previous figure and having the first coat of plaster applied thereto flush with the surface of the wire mesh and the top of the 55 staple; the wire and staple are shown in full for clearness. Fig. 6 is an end eleva-

tion in section along the line 6—6 of Fig. 4, showing to advantage the position the wire mesh assumes when the staple is driven home; the dot-and-dash line indicates the 60 flush surface of the secured wire mesh and holding staple therefor.

In detail, my invention is further described as follows: The numeral 7 indicates 65 in general the spacing member of the two-piece staple, and 8 the complementary securing member. Both members are preferably formed of round wire, and of size and shape best suited for the immediate 70 objects.

The spacing member 7 consists of a continuous length of wire recurved upon itself and forming a U in side elevation, the bars of the U being 9 and 10, and spaced apart a definite distance, and which distance plus 75 the thickness of the layer of wire-mesh lathing 11, determines the thickness of the first coat of plaster 12. Bar 10 of the spacing member is extended and recurved upon itself forming an additional U in plan, Fig. 3, and in a plane different from that of the first-named U. The bar forming the said additional U is 10', and 9' is the terminal bar recurved on bar 10' to form, in elevation, 80 a pair of U's spaced apart, and also spaced apart in plan a sufficient distance to engage 85 the securing member 8 of my staple.

The securing member 8 consists of a length of wire having the major part thereof 90 a driving leg 13, and the remaining part a stop-leg 14 recurved on the former leg but spaced therefrom a desired distance to leave a space 15 for a purpose to be later set forth. At the union of the two legs, the driving 95 head 16 is formed, and the terminal of the stop-leg 14 may be formed with the heel 17. The height from the top of the head to the bottom of the heel, also determines 100 the thickness of the first coat of plaster, and of course, is equal to the aforesaid distance of spacing member plus layer of lathing.

The extremity of the driving leg is pointed, as at 18, and adjacent thereto is an indent 19, adapting the said leg to be 105 locked or engaged in the spacing member in a similar indent 20. The engagement is integral but temporary, and for practical and marketable purposes.

At the free terminations of the spacing 110 member hook-like ends 21 may be formed for stop-engagement with the wire lathing.

In the application of my staple to a

sheathing 22, the customary building paper 23 may first be applied thereto by a few scattering nails (not shown), then the wire-mesh lathing unrolled and applied and the 5 open mouth 24, Fig. 1, of my two-piece, integral staple hooked under a union-strand 25, Fig. 4, and the securing member driven home.

It will be observed from Fig. 6 that the 10 bars 10 and 10' of the U in plan, amply support the building paper 23 on the sheathing 22 with a broad and blunt surface, which eliminates paper cutting and restrains the action of the wind tending to get behind 15 the paper and blow it off, or tear it into strips as is done in cases where small headed or sharp paper-holding means are used. Also from this figure, it will be noted that the uppermost bars of the spacing member 20 serve as a cradle to nest the lathing strands 25 there between and in the space 15 of the securing member 8, when the latter is in final holding and seating position. The final position of all the elements are shown 25 to advantage in Fig. 5, and with the plaster floated flush with the top of the lathing 11 and the top of the driving head 16, the heel 17 gaging the thickness of the plaster and in addition offering another support for the 30 paper 23.

What I claim as new and desire to secure by Letters Patent is the following:

1. A furring staple consisting of a spacing member of wire and a securing member 35 of wire, said spacing member comprising two U-shaped members which have legs

united to form securing means for attachment to said securing member.

2. A furring staple consisting of a spacing member of wire and a securing member 40 of wire, said spacing member comprising two U-shaped members which have legs united for attachment to said securing member, said securing member and said spacing member being normally temporarily held 45 together as a unit.

3. As an element of a two-part staple, a member of wire having midway of its length a curvature adapted to engage the other staple part, and the remainder of the 50 member consisting of a formation of parallel bars spaced a fixed distance from said curvature for spacing purposes.

4. As an element of a two-part staple, a member of wire having midway of its 55 length a curvature adapted to engage the other staple part, and the remainder of the member consisting of a formation of parallel bars spaced a fixed distance from said curvature for spacing purposes and the ends 60 of the member terminating in upturned hooks.

5. As an element of a two-part staple, a securing member of wire having a sharpened driving leg and a comparatively short and blunt stop-leg, the latter leg turned at its 65 extremity to form a heel, and the former leg provided near its extremity with an indent to engage the other staple-part.

In testimony whereof I affix my signature.

OTTO W. JOHNSON.
